UNITED STATES PATENT OFFICE.

FRANZ A. FULLER, OF NEWARK, NEW JERSEY.

SAFETY-RAZOR.

1,290,963.

Specification of Letters Patent.

Patented Jan. 14, 1919.

Application filed May 8, 1915, Serial No. 26,690. Renewed June 8, 1918. Serial No. 239,045.

To all whom it may concern:

Be it known that I, FRANZ A. FULLER, a citizen of the United States, residing in the city of Newark, in the county of Essex and State of New Jersey, have invented certain new and useful Improvements in Safety-Razors, of which the following is a full, clear, and exact description, such as will enable others skilled in the art to which it pertains to make, construct, and use the same, reference being had to the accompanying drawings, and to numerals of reference marked thereon, forming a part of this specification.

15 The object of my invention is the production of a safety razor which shall be simple in construction, comparatively inexpensive in cost, and provided with means for securely holding a detachable blade in position, and also provided with means for securing a detachable razor blade sharpening device thereto.

With this end in view, my invention consists in certain novelties of construction and 25 arrangements of parts, as hereinafter set forth and pointed out in the claims. While the preferred forms of my invention are illustrated in the accompanying drawings, yet it is to be understood that minor detail 30 changes may be made without departing from the scope thereof.

In the accompanying drawings,

Figure 1 represents a side elevation of my improved safety razor, with a removable 35 razor blade sharpening device secured thereto, showing the cutting edge of the razor blade in engagement with the roller of the sharpening device.

Fig. 2 represents, on an enlarged scale, a 40 fragmentary side elevation of my improved safety razor.

Fig. 3 represents a similar view, showing the blade holder in a vertical position.

Fig. 4 represents a sectional side elevation 45 taken on line α — α of Fig. 5; and

Fig. 5 represents a fragmentary front elevation, showing the blade holder in a vertical position.

Similar numerals of reference refer to like 50 parts throughout the specification and drawings.

In the drawings, the numeral 1 represents a blade removably retained in a blade holder 2, said blade holder consisting preferably of 55 a piece of sheet metal, bent upon itself so as to provide resilient clamping jaws to receive

the razor blade between themselves, and further bent to receive a pintle 3, the ends of which are enlarged or riveted over as at 4, and by means of which the blade holder is 60 slidably and pivotally connected to the frame 5. This blade holder is also provided with two pressed-out portions 23 on one of the clamping jaws of the blade holder, to engage with two apertures in the blade 1 to firmly 65 secure and prevent the accidental displacement of the blade 1 from said holder 2.

The frame 5 is preferably made of sheet metal, stamped and formed from a single blank, and so constructed as to grip the 70 blade 1 at the front corners, the sharpened edge of the blade resting upon the bent-over guard 6, which is provided with the usual perforations 7, the free end of which is bent downwardly and which is sufficiently in advance of the edge of the blade to afford the necessary protection against accidental cutting.

The forward and outer end of the guard 6 has upwardly and rearwardly extending 80 stops 8, for engagement with the corners of the cutting edge of the blade 1, to prevent said cutting edge from projecting too far beyond the guard 6, to at all times maintain the cutting edge of the razor blade in the proper and adjusted position relative to the guard teeth. These stops 8 may, for convenience sake, be formed integral with the frame 5.

9 represent upwardly extending side 90 pieces formed integral with the frame 5, each side piece being provided with an elongated slot 10, to receive the end of the pintle 3, by means of which the blade holder 2 is slidably and pivotally mounted in the 95 frame 5. A handle 11, provided with two outwardly extending curved arms 12, is secured to the under side of the frame 5 by means of rivets 13.

Near the front edge of the frame 5, adjacent to the guard 6, and extending preferably across the entire frame, I provide a pressed-out portion 24, designed as a guide, which, together with the ends 25 of the blade holder 2, which also serve as guides, 105 provide convenient means assisting the cutting edge of the blade to engage with the stops 8, the ends 25 being designed to have sliding engagement with the upwardly extending side pieces 9 of the frame 5. These 110 ends 25 also serve as convenient stops, which engage with the rear edge of the frame 5,

to limit the rearward movement of the blade holder 2.

An elongated slot 14 is centrally arranged in the frame 5, to receive the rectangular lug 15, which is preferably formed integrally on the under side of the blade holder 2, and by means of which, together with the locking bar 16, the blade is locked in its adjusted position.

10 The locking bar 16 is slidably mounted in a housing 17, which is secured to the under side of the frame 5 by means of integral lugs 18 passing through suitable apertures in the frame 5, and clenched over, as clearly indicated in Figs. 4 and 5 of the drawings. A portion of the housing, adjacent to the slot 14, is cut away as at 20, to the same depth as the rear of the slot 14, to receive the rectangular lug 15, formed on the blade holder 2. The locking bar is preferably a piece of flat sheet metal, stamped and formed from a single blank, and provided with down-turned ends or push members 28, whereby the locking bar can be moved in either direction.

15 19 represents a recess or cut-away portion, extending inwardly from the front edge of the locking bar, so that when the locking bar is moved as far as possible in 30 one direction, the recess or cut-away portion 19 thereof, will register with the slot 14, and permit the lug 15 of the blade holder 2 to pass through the slot 14 of the frame 5, and through the recess 19, as well as through 35 the cut-away portion 20 in the housing 17, in order that the locking bar might be moved as far as possible in the opposite direction, thereby causing the edge of the locking bar, adjacent the recess 19, to engage with the lug 15, to lock the blade holder with its attached blade, in its adjusted position.

20 An elongated slot 21 and an integral loop 22 arranged adjacent to said slot, is formed 45 near the rear edge of the frame 5, to provide means for securing a razor blade sharpening device, forming the subject matter of a co-pending application, and by means of said device, the cutting edge of the blade, 50 lying adjacent to the guard may be sharpened without removing the blade from the frame.

To operate my razor, the blade holder 2, with a razor blade therein, is moved from 55 the position illustrated in Fig. 2 of the drawings, into the position illustrated in Figs. 3, 4 and 5, by moving the locking bar 16 in the direction of the arrow as indicated in Fig. 5, into the position shown in dotted 60 lines in said figure, thereby causing the locking bar to become disengaged from the rectangular lug 15 of the blade holder. The blade holder 2, with its attached blade, is then moved over the guide 24 and side pieces 65 9, thereby disengaging the cutting edge of

the blade from the stops 8. After the blade holder has been moved into the position shown in dotted lines in Fig. 3, it is then swung into the vertical position shown in said figure, in order to cleanse the blade or 70 to remove the same from the holder, or to attach the sharpening device 26, said sharpening device being provided on its under side with a lug corresponding to the lug 15, whereby the said device is locked to the 75 frame 5 in substantially the same manner as the blade holder 2.

The present invention provides a very efficient and exceedingly simple safety razor, the same being constructed of a minimum 80 number of parts, and reduced to the simplest operative efficiency, said parts being of such shape as to lend themselves readily to manufacture by the use of suitable punches and dies from ordinary sheet metal. 85

I am aware that changes may be made in the several arrangements of the various parts, as well as in the details of construction thereof, without departing from the scope of my present invention; hence I do 90 not wish to be limited to the arrangements and combinations of parts as herein shown and described, as obvious modifications will suggest themselves to those skilled in the art. 95

I claim:

1. A safety razor comprising a frame having guard teeth at one edge, a guide for the face of the razor blade extending across the front of the frame, and a handle extending from the other edge, a blade holder provided with holding means hingedly and slidably connected to the sides of said frame; a blade located in said blade holder, and sliding means slidably secured to the under side of said frame having locking engagement with the holding means on the blade holder for positively adjusting the blade relative to the guard teeth on the frame. 100

2. A safety razor comprising a frame having guard teeth at one edge, a guide for the face of the razor blade extending across the front of the frame, and a handle extending from the other edge, a blade holder provided with holding means hingedly and slidably connected in alined slots formed in the sides of said frame, a blade located in said blade holder, and means slidably secured to the frame and having locking engagement with the holding means on the blade holder, for positively adjusting the blade relative to the guard teeth on the frame. 110

3. A safety razor comprising a frame having guard teeth at one edge, a guide for the face of the razor blade extending across the front of the frame, and a handle extending from the other edge, a blade holder provided with holding means hingedly and slidably connected to the sides of said frame, a blade located in said blade 125

holder, and means slidably secured to the under side of the frame, having locking engagement with the holding means on the blade holder for positively adjusting the 5 blade relative to the guard teeth on the frame.

4. A safety razor comprising a frame having a guide and guard teeth at one edge, a 10 guide for the face of the razor blade extending across the front of the frame, and a handle extending from the other edge, a blade holder provided with guides arranged on its opposite sides hingedly and slidably connected in alined slots formed in the sides 15 of said frame, said guides designed to have sliding engagement with the sides of said frame, a blade located in said blade holder, and means secured to the under side of the frame having locking engagement with the 20 blade holder for positively adjusting the blade relative to the guard teeth on the frame.

5. A safety razor comprising a frame having guard teeth at one edge, a guide for the 25 face of the razor blade extending across the front of the frame, and a handle extending from the other edge, a blade holder slidably connected to the sides of said frame, a blade removably located in said blade holder, a 30 housing secured to the under side of the frame, and a locking bar slidably located within said housing, having locking engagement with the blade holder for positively adjusting the blade relative to the guard teeth 35 on the frame.

6. A safety razor comprising a frame having guard teeth at one edge, a guide for the face of the razor blade extending across the front of the frame, and a handle extending 40 from the other edge, a blade holder provided with resilient clamping jaws to receive the blade between themselves slidably connected to the sides of said frame, a blade located between the clamping jaws of said blade 45 holder, a housing secured to the under side of the frame, and a locking bar slidably located within said housing, having locking engagement with the blade holder for posi-

tively adjusting the blade relative to the guard teeth on the frame.

7. A safety razor comprising a frame having a guide and guard teeth at one edge, said 50 guide extending across the front of the frame, and a handle extending from the other edge, said frame being further provided with means for positioning a blade sharpening device thereto, a blade holder hingedly and slidably connected to the sides of said frame, a blade located in said blade holder, and means slidably secured to the 55 frame having locking engagement with the blade holder for positively adjusting the blade relative to the guard teeth on the frame.

8. A safety razor comprising a frame having guard teeth and a guide at one end, said 60 guide extending upwardly and across the front of the frame and a handle extending from the other edge, said frame being further provided with means for positioning a blade- 65 sharpening device thereto, a blade holder provided with resilient clamping jaws to receive the blade between themselves slidably and hingedly connected to the sides of said frame and guided by the tops of said sides, 70 a blade located between the clamping jaws of said blade holder, one of the clamping jaws provided with holding means, a housing secured to the under side of the frame provided with an opening, a locking bar slidably located within said housing provided with a cut-away portion, the holding means formed on one of the clamping jaws designed to be received into the opening in the housing and the cut-away portion of the locking 75 bar and to have locking engagement with the locking bar for positively adjusting the blade holder relative to the guard teeth on the frame.

This specification signed and witnessed 80 this 7th day of May, 1915.
